CLAIM

The ornamental design for a storage device housing, as shown and described.

DESCRIPTION

FIG. 1 is a perspective view of a storage device housing showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a perspective view thereof with a connector arm shown in an alternative position.

The broken line showing of the connector and the interior of the housing, and the unshaded areas therein, are for illustrative purposes only and form no part of the claimed design. The contrast in shading represents a contrast of appearance and does not depict any particular color, texture, or material.
